UNITED STATES PATENT OFFICE

2,001,158

FLYING MACHINE

Richard W. Sears, 2d, and James F. Koca, Woodstock, Ill.; said Koca assignor to said Sears, 2d

Application June 12, 1930, Serial No. 460,604
Renewed August 10, 1933

17 Claims. (Cl. 244—29)

Our invention relates in general to flying machines or air vehicles, and one of the objects of the invention is to provide means for detaching from the fuselage the propelling mechanism.

5 Another object of the invention is the provision of mechanism for adjusting the center of gravity, combined with means for detaching the propelling mechanism so that after the latter has dropped, the remaining structure may continue 10 in flight as a glider.

Another object of the invention is the provision of improved and efficient means for shifting the position of the aeroplane unit comprising the wings, relative to the fuselage.

15 Another object of the invention is the provision of improved and efficient means for shifting the seat of the pilot to positions within reach of a plurality of pilot control levers.

More particularly it is the object of the present 20 invention to provide electrically operated mechanism under the control of the pilot for detaching the propelling mechanism including the propeller engine when the latter becomes inoperative and at the same time shifting the aeroplane unit rearwardly and the pilot seat forwardly from one 25 pilot control lever to another to enable the structure remaining after the propelling mechanism has dropped, to continue in flight as a glider.

Other objects of the invention will appear hereinafter, the novel features and combinations being set forth in the appended claims.

In the accompanying drawings—

Fig. 1 is a side elevation of a complete flying machine or air vehicle embodying our improvements;

Fig. 2 is a sectional elevation of the forward portion of the flying machine to show various novel features;

Fig. 3 is a plan view of the pilot seat and the mechanism for shifting the same longitudinally of the fuselage;

Fig. 4 is a sectional elevation taken on the line 4—4 of Fig. 2 looking in the direction of the arrows 8—8;

Fig. 5 is a sectional elevation on the line 4—4 of Fig. 2 looking in the direction of the arrows 5—5;

Fig. 6 is an enlarged detail view showing the detachable connections to the propelling mechanism; and

Fig. 7 is a sectional plan view on the line 7—7 of Fig. 6.

Fig. 1 shows the fuselage 9 of the flying machine with the usual direction rudder 10 and

elevating rudder 11 at the tail end thereof. To the fuselage are also connected the usual landing wheels 12 and 13.

To the forward end of the fuselage is secured on the transverse plane 14, the propelling mechanism 15 comprising the engine 16 and propeller 17.

The fuselage 9 is preferably metal and its forward end is closed by the transverse metal plate 18 against which fits the rear transverse metal plate 19 of the engine casing 20.

Projecting from the plate 29 through semi-circular openings 21, 21 in the plate 18, are retaining arms 22, 22. These arms are preferably integral with the plate 19 and are each provided with a screw-threaded opening for receiving the screw-threaded portion 23 of the rod 24 as shown in Fig. 6.

Secured rigidly to the rear of the plate 18 as by means of rivets 25, are brackets 26, 26, each of which is screw-threaded as illustrated at 27 in Fig. 6 to receive the screw-threaded portion 23 of the rod 24. The retaining arms 22 fit closely against the outer surfaces of the brackets 26 and the screw threading in the brackets 26 and the arms 22 is exactly alike so that the arms 22 and brackets 26 when in engagement with each other may act as a unit for receiving the screw-threaded portion 23 of the rod 24.

Each of the rods 24 fits into a sleeve 28 and is splined thereto as shown at 29 in Figs. 6 and 7 to permit relative sliding movement between the rod 24 and the sleeve 28, but no relative rotary movement between the same. The sleeves 28 are four in number as illustrated in Fig. 5, but this number may be varied as desired. Each of the sleeves 28 is connected to a rod 30 which has keyed thereto a worm wheel 31. The ends of the rod 30 may be mounted to rotate in the bearings 32 and 33 fixed to the rear of the plate 18.

The gear wheels 31 are arranged in pairs, each pair being in the same plane and the two pairs being in planes intersecting each other and also the axis of the worm 34 which meshes with all four of the worm wheels 31 as shown in Fig. 5.

The worm 34 is mounted on a longitudinal shaft 35 which at its rear end is journaled in the bearing 36 immediately in front of which is located a worm wheel 37. That is to say, the worm wheel 37 is keyed to the shaft 35 to rotate therewith. The worm 38 meshes with the worm wheel 37 and is mounted on a transverse shaft 39 to which an electric motor 40 is connected. As shown in Fig. 4 the electric motor 40 is suspended from the bracket 41 which is secured to one of the inside

walls of the fuselage 9. The shaft 39 may be journaled in the brackets 42 and 43.

In order to have ample support for the central longitudinal shaft 35, a spider bracket having the arms 44 may be provided with the outer ends thereof secured by means of the bracket plates 45, 45 to the rear wall of the plate 18 as shown in Fig. 5. At the center of the arms 44 is a bearing 46 for the longitudinal shaft 35 intermediate the ends of the latter. The bearing 36 may be supported from one of the arms 44 by means of the bracket arm 47 as shown in Fig. 2.

Keyed to the shaft 35 is a sprocket gear 48 located between the bearing 46 and the worm gear 37. Meshing with the sprocket 48 is a sprocket chain 49 as shown in Fig. 4. The sprocket chain 49 is endless and extends downwardly from the sprocket 48 to sprockets 50 and 51 with which the sprocket chain 49 meshes in order to rotate the rods 52 and 53 to which the sprockets 50 and 51 are keyed.

As shown in the plan view in Fig. 3, the rods 52 and 53 are mounted loosely in the brackets 54, 55, 56 and 57 and in the brackets 58, 59, 60 and 61, all of which brackets are connected to the inner walls of the fuselage 9.

As shown in Fig. 3, the side walls of the fuselage 9 are provided with slots 62 and 63 for the inwardly extending arms 64, 65, 66 and 67.

The lifting device which in this instance comprises upper and lower rings 68 and 69 is rigidly connected by means of the struts 70, 71 and the cross-stays 72, 73. The aeroplane comprising upper and lower wings which extend laterally from the fuselage 9 and transversely thereof, constitutes the aeroplane unit and is movable as such longitudinally of the fuselage. The inwardly extending arms 64, 65 and 66, 67 are connected to the aeroplane unit and these inwardly extending arms extend through the guide slots 62 and 63 and are screw-threaded to receive the screw-threaded rods 52 and 53. When the sprocket 48 is rotated the sprockets 50 and 51 and the rods 52 and 53 will likewise be rotated. For instance, if they are rotated in a clockwise direction as viewed in Fig. 4, the aeroplane unit will be moved rearwardly toward its dotted line position shown at 74 in Fig. 2.

The rear ends of the rods 52 and 53 are provided with sprockets which mesh with sprocket chains 75 and 76 as shown in Figs. 3 and 4. These sprocket chains 75 and 76 also mesh with the sprockets 77 and 78 at the rear ends of the rods 79 and 80. The rods 79 and 80 are mounted in bearings 81, 82 and 83, 84 and are screw-threaded through depending brackets 85, 86 and 87, 88 secured to the bottom of the pilot's seat 89. The seat may be double as shown in Fig. 3 to carry another person in addition to the pilot. Within reach of the pilot is the operating lever 80 which controls the various elements in the flight.

The connections are such that when the aeroplane unit is in its full line position as shown in Fig. 2, the pilot's seat is in its rearward position as shown in full lines in Fig. 2. When the aeroplane unit is shifted to its dotted line position shown at 74 in Fig. 2, the pilot's seat is shifted forward to its position shown at 91 in Fig. 2 and at such time the pilot will be within reach of a duplicate operating lever 92. Therefore the pilot may control the propelling mechanism from his seat whether in the position shown in full lines in Fig. 2 or in the position shown in dotted lines in Fig. 2. Whether the seat is rearward or forward he has within his reach the reversing switch

93 which is connected between the storage battery 94 and the electric motor 40. The pilot may therefore operate the motor 40 in either direction to shift the aeroplane unit rearwardly while at the same time shifting his own seat forwardly, thereby adjusting the center of gravity of the flying machine.

It should also be noted that the pilot may operate the detaching mechanism and drop the propelling mechanism from the fuselage when the engine becomes inoperative. The connections are preferably such that when the switch 93 is placed in proper position the rods 24 will each be rotated in such direction as to withdraw the screw-threaded portions 23 from the retaining arms 22 and as soon as this has been completely effected, the propelling mechanism will become completely detached and will drop from the fuselage, the semi-circular openings 21 being sufficiently large to permit free withdrawal of the retaining arms 22 from the plate 18.

At the same time that the detaching mechanism is being operated by the electric motor 40 the sprocket chain 49 is being driven and the aeroplane unit is being moved rearwardly longitudinally of the fuselage toward its dotted line position 74. At the same time, the pilot's seat is being moved forward toward its dotted line position 91. Therefore when the propelling mechanism is dropped off, the remaining structure will be properly balanced as to center of gravity and air lifting pressures to permit the pilot to continue in flight while the machine is acting as a glider, thus permitting him to make a safe landing, whereas with a very heavy engine the machine may get completely out of his control in his efforts to glide to a safe landing. After the propelling mechanism has been detached and has dropped, the pilot may control the remaining structure as a glider by shifting at will his seat and the aeroplane unit by operating the reversing switch 93 to open and closed positions on either side of the pivot thereof.

Both sets of worm gearing 34, 31, and 38, 31 are self-locking so that they will be operable only by the power from the electric motor 40 and not by vibration or otherwise.

We wish it also to be understood that the screw-threaded portions 23 of the rods 24 may be lengthened so as to allow a limited amount of adjustment of the aeroplane unit and of the live load without dropping off the propelling mechanism, in order to vary the center of gravity to compensate for distribution of the weight of passengers, freight and fuel carried in addition to the pilot.

Obviously those skilled in the art may make various changes in the details and arrangement of parts without departing from the spirit and scope of the invention as defined by the claims hereto appended and we wish therefore not to be restricted to the precise construction herein disclosed.

Having thus fully disclosed an embodiment of our invention, what we desire to secure by Letters Patent of the United States is:

1. In an aeroplane, the combination with a fuselage, of propelling mechanism connected thereto, and means under the control of the pilot for detaching the propelling mechanism and for simultaneously readjusting the center of gravity of the remaining structure, said means including members for shifting certain parts of the machine to compensate for the removal of the propelling mechanism.

2. In a flying machine, the combination with a fuselage, of an aeroplane unit adjustably mounted thereon, mechanism for shifting such unit longitudinally of said fuselage, mechanism for shifting the live load to vary the center of gravity of the machine as a whole, and power-operated means under the control of the pilot for operating simultaneously both of said shifting mechanisms. 5
- 10 3. In a flying machine, the combination with a supporting frame, of propelling mechanism detachably connected thereto, an aeroplane unit adjustably mounted on said frame, a seat for the pilot, mechanism for shifting said seat forwardly while said unit is shifted rearwardly, and power-operated mechanism controlled by said pilot to release said propelling mechanism to drop the same while said machine is in flight, said power-operated mechanism also operating said shifting mechanism to adjust the center of gravity and the position of said unit to enable the structure remaining in flight to act as a glider. 10
- 15 4. In a flying machine the combination with a fuselage, of detachable propelling mechanism therefor, an aeroplane unit, mechanism for adjusting the position of said unit longitudinally of said fuselage, and power-operated mechanism for detaching the propelling mechanism to drop the same and for adjusting the position of the aeroplane unit to enable the structure remaining in flight to act as a glider. 15
- 20 5. In a flying machine, the combination with a fuselage, of propelling mechanism detachably connected thereto, an aeroplane unit adjustably mounted on said fuselage, mechanism for shifting said unit longitudinally of said fuselage, means for detaching said propelling mechanism to drop the same from the fuselage, worm gearing connected to said shifting mechanism and said detaching means to operate both simultaneously to effect rearward movement of the said unit while said propelling mechanism is being detached, and a motor for driving said worm gearing. 20
- 25 40 6. In a flying machine, the combination with a fuselage, of an aeroplane unit adjustably mounted thereon, an adjustable pilot seat, detachable propelling mechanism, means comprising screw-threaded rods extending longitudinally of the fuselage to shift the said aeroplane unit rearwardly and said pilot seat forwardly simultaneously, mechanism for detaching said propelling mechanism to drop the same from the machine, and mechanism operable by a single 30
- 35 50 55 source of power for shifting said unit rearwardly and shifting said pilot seat forwardly while detaching the propelling mechanism to enable the structure remaining after the motor has dropped to continue in flight as a glider. 35
- 60 7. In a flying machine, the combination with a fuselage, of a pilot seat having a forward position and a rear position, separate pilot operating levers one for one position of said seat and the other for the other position thereof, and power-operated mechanism under the control of the pilot for shifting his seat to either of said positions. 40
- 65 8. In a flying machine, the combination with a fuselage of propelling mechanism detachably connected thereto, an aeroplane unit adjustably mounted on said fuselage, a pilot seat shiftable forwardly and rearwardly, separate pilot control levers one within reach of the pilot when his seat is forward and the other when his seat is rearward, mechanism for detaching the propelling 45
- 70 75 mechanism, mechanism for shifting said unit longitudinally of said fuselage, mechanism for shifting said seat, gearing connecting said detaching mechanism to said shifting mechanisms to cause said unit to be shifted rearwardly and said seat to be shifted forwardly while said propelling mechanism is being detached, and power-operated mechanism under the control of the pilot for operating all of the aforesaid mechanisms and after the propelling mechanism has dropped to adjust the position of his seat and the position of said aeroplane unit relative to said fuselage while the structure remaining after the propelling mechanism has dropped acts as a glider. 5
- 15 9. In an aeroplane, the combination of a fuselage and a propelling mechanism, including a prime mover, a first control member and a second control member, and a seat for the pilot normally disposed with respect to one of said control members for permitting the shifting of said control member by the pilot when he is in such seat, and means under the operation of the pilot when he is in his seat for shifting said seat longitudinally of the fuselage and adjacent to said second control member. 20
- 25 10. In an aeroplane, the combination of a fuselage and a propelling mechanism therefor, including a relatively heavy power unit, a seat for the pilot, and wings, said wings and pilot seat being longitudinally shiftable of the fuselage, means under the control of the pilot and actuatable after a predetermined period of operation for automatically detaching the power unit from the fuselage, and means actuatable during said predetermined movement for shifting the wings and pilot seat longitudinally of the fuselage, whereby to balance the center of gravity. 30
- 35 11. In a flying machine having a number of parts, means under the control of the pilot for dropping one of said parts while the machine is in flight, and means for changing the center of gravity of the remaining structure including mechanism for shifting a certain part thereof relative to the other remaining parts. 40
- 45 12. In a flying machine, the combination with a main frame of propelling mechanism connected thereto, and means under the control of the pilot for detaching the propelling mechanism and for changing the center of gravity of the remaining structure, said means including members for shifting certain parts of the machine to compensate for the removal of the propelling mechanism. 50
- 55 13. In an aeroplane, the combination with a main frame of propelling mechanism connected thereto, means under the control of the pilot for detaching the propelling mechanism and for adjusting the center of gravity of the machine including mechanism for shifting certain parts thereof, said mechanism being operable within certain limits prior to the detachment of the propelling mechanism. 60
- 65 14. In an aeroplane, the combination with a main frame of propelling mechanism connected thereto, means under the control of the pilot for detaching the propelling mechanism and for adjusting the center of gravity of the machine including mechanism for shifting certain parts thereof, said mechanism being operable within certain limits prior to the detachment of the propelling mechanism and being operable within greater limits after the detachment of the propelling mechanism to compensate for its removal. 70
- 75 15. In a flying machine, the combination with 75

a main frame of propelling mechanism connected thereto, a seat shiftable with respect to the frame and movable between two positions, controls for the flying machine at each of said seat 5 positions, and means for detaching the propelling mechanism from the machine while the machine is in flight and for shifting the seat from one to the other of said positions.

16. In an aeroplane, the combination with a 10 fuselage, of a lifting unit adjustably mounted thereon, mechanism for shifting such unit longitudinally of the fuselage, a seat, mechanism for shifting said seat longitudinally of the fuselage to vary the center of gravity of the aeroplane 15 as a whole, and power operated means under the

control of the pilot for operating simultaneously both of said shifting mechanisms.

17. In an aeroplane, the combination with a 5 fuselage, of a lifting unit adjustably mounted thereon, mechanism for shifting such unit longitudinally of the fuselage in one direction, a seat, mechanism for shifting said seat longitudinally of the fuselage in the opposite direction to vary the center of gravity of the aeroplane as a whole, and power operated means under the control 10 of the pilot for operating simultaneously and in predetermined speed relation both of said shifting mechanisms.

RICHARD W. SEARS, II.
JAMES F. KOCA. 15
